UNITED STATES PATENT OFFICE.

HARRY T. KRAKAU, OF CLEVELAND, OHIO, ASSIGNOR TO THE NATIONAL MALLEABLE CASTINGS COMPANY.

PIVOTAL CONNECTION FOR LOCOMOTIVES OF THE MALLETT ARTICULATED TYPE.

1,090,631.

Specification of Letters Patent. Patented Mar. 17, 1914.

Application filed August 31, 1912. Serial No. 717,991.

To all whom it may concern:

Be it known that I, HARRY T. KRAKAU, a citizen of the United States, and residing at Cleveland, Cuyahoga county, Ohio, have 5 invented an Improvement in Pivotal Connections for Locomotives of the Mallet Articulated Type, of which the following is a specification, reference being had to the accompanying drawings, in which—

10 Figure 1 is a bottom plan view showing my improved connection as applied to two engines of a Mallet articulated locomotive; Fig. 2 is an enlarged bottom plan view of the connection partly broken away; Fig. 3 15 is an elevation of the connection partly in section; Figs. 4, 5 and 6 are diagrammatic views of the two engines of a locomotive illustrating various conditions met in service; Fig. 4 showing the locomotive passing 20 around a continuous curve; Fig. 5 showing the locomotive passing from a tangent to a curve, and Fig. 6 showing the locomotive having its two engines passing over a reverse curve.

25 My invention relates to pivotal connections for locomotives and is especially designed to connect the high and low pressure engines of the Mallet articulated type.

The objects of my invention are to permit 30 radial movement and vertical angling between the two parts of the locomotive without strain upon the frame of the locomotive itself or upon the track rails.

Referring to the drawings, 2 is the leading 35 or low pressure engine and 3 is the trailing or high pressure engine. The engines 2 and 3 are connected by a casting 4 which is attached to the trailing or high pressure locomotive by means of a vertically disposed pivot pin 5. The casting 4 has a rectangular shaped aperture 6 for the reception of the bearing block 7, which takes about the pin 5, and which is adapted to slide laterally and horizontally in the aperture or slot 6. The pin 5 is carried in registering apertures 8 of the studs 9 which project from the cross frames 10, and the cross frames 10 are suitably secured to the main frames 11 of the engine 3. The studs 9 45 also hold the bearing block 7 in place in the slot 6 of the casting 4.

The casting 4 has at its forward end arms 12, which are apertured for reception of the horizontally disposed pivots 13. The pivots 13 are mounted on lugs 14 of the cross

framing 15 carried by the main frames 16 of the engine 2, and are held in place by the heads 17 and by the bolts 18. This horizontally disposed pivotal connection 13 permits vertical angling between the two engines of the locomotive when the locomotive passes over an elevation or depression in the track.

In Figs. 4, 5 and 6 I have shown the manner in which the connection between the two engines of a locomotive is displaced laterally. In Fig. 4 the entire locomotive is on a continuous curve, and the pivotal point 5 between them does not lie over the center of the track, but as the pivotal point 65 is displaced laterally toward the outside of the curve by substantially the same amount on both parts of the locomotive, because the distance between the pivotal point and the track center is the same in both engines, the strain upon the parts is not serious. In Fig. 5 the pivotal point of the leading engine, which is on the curve, is displaced laterally of the center of the track while the pivot of the trailing engine, which is on 70 the straight track, lies over the center of the track. This condition puts a certain amount of strain or stress on the frames of the engines if the locomotive is equipped with the fixed pivotal point now in use on 75 these types of locomotives, since the pivotal point of the trailing engine would lie normally at the center of the track and the pivotal point of the leading engine would lie off center toward the righthand or outside rail. When a reverse curve is met, such as is shown in Fig. 6, the amount of stress and strain on the frames of the locomotive is greatly increased. In Fig. 6 it will be 80 seen that the pivot of the leading engine is 85 displaced toward the righthand rail, and the pivot of the trailing engine is displaced toward the lefthand rail, and that if a fixed 90 instead of the sliding pivot of my invention is employed, that the stress and strain upon 95 the frames of the locomotive is extreme, and the danger of derailment, either from the spreading of the rails or from the wheels 100 leaving the track, serious. The frames in Fig. 6 are shown in the positions which they 105 normally occupy without strain, and these positions are also the positions they are permitted to occupy by the employment of my invention. It will therefore be seen that my 110 device is adapted to provide a connection

between the two engines of a locomotive of the Mallet articulated type which will eliminate all lateral stresses and strains due to the curving of the track and will also prevent any stress or strain upon the locomotive due to elevations or depressions in the track.

It is obvious that many changes may be made in the device which I have shown and described herein without departing from my invention.

What I claim is:

1. In a locomotive of the Mallet articulated type, a connection between the two engines thereof, said connection comprising a member of substantially U-shape pivoted to one engine to swing in a vertical plane, and lying normally in a horizontal plane, said member having a rectangular aperture, a bearing block slidably mounted in said aperture, carried by the said member, and

a pin mounted on the other engine and passing through said bearing block.

2. In a locomotive of the Mallet articulated type, a connection between the two engines thereof, said connection being comprised of a rectangularly shaped horizontally disposed member having an aperture therein, the said member being pivoted to one engine by a horizontally disposed pivot and to the other engine by a vertically disposed pivot, a bearing block mounted in and carried by the said member taking about the vertically disposed pivot, the said bearing block being held from vertical movement and being free to move in said aperture laterally in a horizontal plane.

HARRY T. KRAKAU.
